(57) **CLAIM**

The ornamental design for a stand for a TV receiver, as shown and described.

DESCRIPTION

FIG. 1 is a front, right side, perspective view of a stand for a TV receiver showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a reference view showing the state in which the subject design is installed on the TV receiver thereof; and,

(Continued)

FIG. 9 is a reference view showing the state in which the subject design can be separated from or combined with the TV receiver.

The broken lines shown in FIGS. 8 and 9 that show the tv receiver illustrate environment and form no part of the claimed design.

1 Claim, 8 Drawing Sheets

(58) Field of Classification Search

CPC . A47K 2201/001; F16B 47/00; F16B 47/006
